SPINNING-RING.

1,173,723.

Specification of Letters Patent. Patented Feb. 29, 1916.

Application filed December 16, 1915. Serial No. 67,101.

To all whom it may concern:

Be it known that I, CHARLES D. LANNING, a citizen of the United States, and a resident of Boston, in the county of Suffolk and 5 State of Massachusetts, have invented an Improvement in Spinning-Rings, of which the following description, in connection with the accompanying drawings, is a specification, like characters on the drawings representing like parts.

This invention relates to spinning rings and to combined spinning rings and travelers therefor.

In order that the principle thereof may 15 be readily understood, I have disclosed certain embodiments thereof in the accompanying drawing, wherein—

Figure 1 is a plan view of a ring embodying my invention; Fig. 2 is a vertical, 20 central section of the ring shown in Fig. 1; Fig. 3 is a view similar to Fig. 2, but representing a ring stamped or bent from sheet metal; and Fig. 4 represents a duplex or reversible type of ring embodying my invention.

From a commercial standpoint, it is important that the traveler be symmetrical or double-ended in form, so that the operator need not exercise special care in placing it 30 upon the ring in a particular relation. The ring of my invention is primarily intended for use in connection with the ordinary commercial traveler, which is herein represented at 1 as of bowed form and having 35 inturned ends 2, 3.

An important object of my invention is to provide a ring of any suitable material and either forged or stamped from sheet metal and of such a character and so proportioned that, without increasing the radial dimension of the upper flange but on the contrary employing an upper flange of the usual radial dimension and with the usual traveler, the web or body wall of the 45 ring supporting the upper flange is so formed that the outer end 2 of the traveler, when thrown out in action by centrifugal force, does not or cannot contact with the outer surface of the web, or its contact 50 therewith is much limited as compared with the usual conditions. It is of exceeding importance from a commercial standpoint

that the length of the traveler be kept down so as to limit the weight thereof. The necessary form of the traveler is such as to 55 engage the ring or traveler flange, and since the outer end of the traveler is thrown down by centrifugal force, it is necessary that the traveler be bowed upwardly and engage the traveler flange loosely, so that in brief 60 it will run as free of contact as possible. The limited length of the traveler limits the width radially of the ring or traveler flange, and this limits the thickness of the web or body under the flange. Within the commercial or practical art limits, with a body or 65 web wall having a straight or vertical outer surface, the outer portion of the traveler is thrown down by centrifugal force into contact with the web wall. Preferably employing a traveler flange of normal radial dimension and preferably employing a bowed traveler of ordinary construction, I so shape and form the inner and outer surfaces of the web or body of the ring as to provide 70 surfaces with which the traveler will not make contact when thrown down at its outer end by centrifugal force.

In Fig. 2, I have represented a ring produced by forging, machined down and then 80 case-hardened and polished. The said ring is provided with an upright body 4 and an annular foot or base 5 resting upon or received by an annular ring 6, here shown as having struck up lugs 7 to embrace the 85 base 5.

The outer wall of the web from its junction with the traveler flange 8 slopes inwardly and downwardly as represented at 9, the condition to be established being such 90 that with the traveler in the position assumed under centrifugal force its outer portion can be rocked upwardly and downwardly without its outer end 2 touching the portion 9 of the body or web 4. The inwardly and downwardly sloping portion 9 is carried down sufficiently far so that when the under side of the bowed portion of the traveler contacts or approaches contact with the upper portion of the traveler flange 8, 95 the outer end of the traveler cannot contact with substantial friction with the outer surface of the body 4. Preferably also with the traveler flange and traveler of the usual 100

dimensions, it is important to form the inner surface of the web or wall 4 of the ring with an inwardly and downwardly sloping surface 10 from the point of junction with the traveler flange. This prevents contact of the inner end of the traveler 3 with the inner surface of the body or web 4 of the ring as the traveler moves into position in operation. It is not essential that both the inner and outer surfaces of the body 4 be formed or shaped as described, but preferably and to effect the best results, I do so shape or form them. I regard the shape or formation of the outer surface of the body as of the greater importance, but it is particularly desirable that the inner surface be shaped for the purpose stated, so that in the necessarily quick starting up of the traveler after picking up, the traveler shall not come in contact with the ring at any portion except the inner edge of the traveler flange.

The traveler flange may be of any suitable character, but preferably it is provided with a thin outer edge 11 of substantially the character shown in the patent to Cunniff No. 1,161,800, the inner edge 12 of said flange being of markedly greater thickness and the upper surface 13 of said flange sloping downwardly and outwardly to said thin outer edge. The upper surface of said traveler flange may slope down in any suitable manner, but preferably either obliquely or with a concaved or recessed formation.

The desideratum in ring and traveler combinations is uniformity of friction between the ring and traveler during the spinning operation. The traveler is subjected to more or less upward and downward rocking strains due to the traverse of the ring rail, the different diameters of the bobbin onto which the yarn is laid, the uneven pull upon the yarn and other causes. In general, the heaviest traveler that can be used under given conditions is preferred, though sometimes the lightest permissible traveler is employed, so as to obtain soft yarn. The main factor in securing uniformity of friction is freedom of the traveler in operation so far as possible from contact with the ring at any other place than the inner edge of the upper flange against which the traveler is necessarily thrown by centrifugal force. As heretofore pointed out, the traveler is under best conditions of an open bow form, the distance between the ends of the traveler being such as to lock it in engagement with the traveler flange. The permissible weight of the traveler is in most cases very small and generally speaking its length establishes its weight, most commercial travelers being of uniform cross section. Such necessary limitation of weight and length of traveler consequently brings about a resulting limitation in the radial dimension of the traveler

flange. Such traveler flange is necessarily supported by a body or web, and the radial dimension or thickness of such body or web is sharply limited, particularly at and near its junction with the traveler flange. The necessarily upwardly bowed form of the traveler is such that as a result of its position in operation under centrifugal force, the outer end of the traveler is thrown downwardly, so that said traveler end tends to contact with the outer surface of the body of the ring, and thereby to cause undesirable and irregular friction. Merely lengthening the radial dimension of the traveler flange of the ring and moving the body or web of the ring in nearer the inner edge of the traveler flange than the outer edge thereof does not in practice solve the problem, for, as the radial dimension of the upper flange is lengthened, the traveler must necessarily be lengthened, its general center of gravity is raised, and it consequently tends to throw into a lower position at its outer end under centrifugal force, thus causing contact between the outer end of the traveler and the outer surface of the body or web of the ring. I have solved these various problems and provided a ring with which, if desired, I may employ the ordinary or commercial form of traveler, and wherein the contact between the outer end of the traveler and the outer surface of the body of the ring is eliminated or reduced to a minimum, and where contact is also eliminated or substantially eliminated between the inner end of the traveler and the inner surface of the body of the ring.

As heretofore stated, the ring may be formed in any suitable manner. In Fig. 3, I have shown a ring having the characteristics of the ring shown in Fig. 2, and of substantially the same shape, the ring, however, being stamped from sheet metal, the inner portion of the traveler flange being therefore bent upon itself.

Within the scope of my invention, the ring may have a single or double traveler flange. In those forms shown in Figs. 2 and 3, the ring is provided with a single flange. In that form of my invention shown in Fig. 4, I have provided two traveler flanges 14, 15, each preferably having a thin outer edge 16, thus rendering the ring readily reversible. Such ring may be supported upon a basal ring 6 or other suitable support in any desired manner.

In order to render the ring reversible and to give it the characteristics of the ring shown in Figs. 2 and 3, the outer wall of the body is inwardly and downwardly sloped at 17 and the lower part thereof is upwardly and inwardly sloped at 18 to a preferably median circumferential line 19, the inner surface of the upper portion of said body being inwardly and downwardly sloped at 20

20, and the lower portion thereof being upwardly and inwardly sloped at 21 to a preferably median zone 22. The ring is thereby rendered readily reversible, and in either 5 position thereof, the inner and outer ends of the traveler are preserved from contact with the body of the ring in the spinning operation.

Obviously that form of my invention 10 shown in Fig. 4 may be forged or formed from sheet metal and stamped into shape.

The ring of my invention is in its preferred embodiment a consequence of the requirement for small weight of the traveler, the 15 necessary limitation of the length of the traveler as necessarily upwardly bowed tending to raise the center of gravity and tending to throw the outer end of the traveler down in operation under centrifugal force, the necessary 20 limitation of radial dimension of the traveler flange, the necessary existence of the inner and outer parts of the traveler flange, and the necessary limitation upon the radial dimension of the body or upright 25 portion of the ring, and particularly the radial dimension of the body at and adjacent to the under side of the traveler flange.

It will thus be evident that the various 30 features enumerated combine in the production of a unitary result, and that while my invention is not in all respects limited thereto, the ring herein disclosed particularly combines and coöperates with a traveler of bowed form having inwardly turned ends 35 and of a normal length.

The thin, outer edge of the traveler flange coöperates also with the other feature of the ring and traveler in that not only is the contact between the ends of the traveler 40 and the body of the ring eliminated or reduced to a minimum, but the contact between the outer portion of the traveler flange and the under side of the traveler is also reduced to a minimum. In view of the 45 fact that the outer end of the traveler is maintained at all times out of or substantially out of contact with the outer wall of the body, it is easier to thread the end into the eye. This can be done by passing 50 the end up in contact with the wall of the ring and depressing the traveler, so that the thread passes into the space between the traveler and the ring.

The preferred form of the invention and 55 the main advantages growing out of the same may be set forth as follows: The traveler must engage the ring flange. In all commercial practice it runs above the ring flange. Due to its form, the center of gravity is necessarily above the plane of contact 60 of the traveler with the flange when the traveler is pulled up against the flange, with both ends touching. Consequently when centrifugal force throws the traveler out 65 so that its inner bend is in contact with the

inner lip of the flange, the outer end of the traveler is thrown downwardly and its outer terminal swings inwardly.

No departure from a traveler made of wire of uniform cross section is desirable. 70 Convenience requires that it be symmetrical so that no care is required as to the end which is put inside. Any weight added to the lower portion of the traveler to lower its center of gravity is objectionable. If put 75 only on the inner end it makes an undesirable single-ended traveler. If put on both ends, or the outer end, it tends to increase the breaking strain on the traveler, resulting from centrifugal action. And fundamentally limitation of weight is essential in order that the operative friction resulting from 80 rotation at high speed shall be kept at a minimum.

It being necessary to keep the weight of 85 the traveler down, its length must be kept down. The result is that the radial width of the ring flange must be kept down. The result of this is that the thickness of the supporting wall under the ring flange must be 90 kept down. The result of these conditions is that when under centrifugal force the traveler is thrown out, and its outer end is thrown downwardly and its outer terminal is swung inwardly, the outer terminal tends 95 to contact with the outer surface of the supporting wall under the ring flange. It is fruitless to endeavor to avoid this by increasing the radial width of the ring flange, and moving the supporting wall nearer the 100 inner lip than the outer lip of the ring flange. For this means that the traveler has to be increased in length. Its weight is therefore increased. Due to its form, its center of gravity thus tends to be raised 105 rather than lowered, since most of its substance is in its upper portion; and, consequently, the longer it is, the more its outer portion tends to throw downwardly under centrifugal action, and the body of the traveler tends to be thrown into contact with the upper portion of the outer edge of the ring flange. The general result is that the object of preventing friction other than 110 between the inner bend of the traveler and the inner lip of the ring flange can be best accomplished, and, perhaps, only accomplished, under commercial limitations of 115 weight and length of traveler, by preserving the usual dimensions and weights of traveler and ring flange, and by sloping the supporting wall inwardly and downwardly so that it lies in such position that the outer terminal of the traveler cannot contact with it in operation.

Having thus described one illustrative embodiment of my invention, I desire it to be understood that although specific terms are employed, they are used in a generic and descriptive sense and not for purposes of 120 125 130

limitation, the scope of the invention being set forth in the following claims.

Claims:

1. A spinning ring having an upright body and a traveler flange, the outer surface of said body adjacent the traveler flange sloping inwardly and downwardly sufficiently to permit the outer portion of the traveler being rocked in operation without substantial contact of its outer end with such sloping portion.

2. A spinning ring having an upright body and a traveler flange, the inner wall of the body adjacent said flange sloping inwardly and downwardly to prevent substantial contact in operation of the inner end of the traveler with the inner wall of the body.

3. A spinning ring having an upright body and a traveler flange, the inner and outer walls of said body adjacent said flange sloping inwardly and downwardly sufficiently to prevent substantial contact in operation of the inner and outer ends of the traveler with said walls of the body.

4. In combination, a traveler of open, bowed form and of substantially uniform cross section with its ends spaced apart less than the radial dimension of the traveler flange and a spinning ring, the outer wall of the body adjacent the traveler flange sloping inwardly and downwardly sufficiently to permit the outer portion of the traveler being rocked in operation without substantial contact of its outer end with such sloping portion of the body.

5. In combination, a traveler of open, bowed form and substantially uniform in cross section with its ends spaced apart less than the radial dimension of the traveler flange, and a spinning ring, the inner surface of the body thereof adjacent said flange sloping inwardly and downwardly to prevent substantial contact in operation of the inner end of the traveler with the inner wall of the body.

6. In combination, a traveler of open, bowed form and of substantially uniform cross section with its ends spaced apart less than the radial dimension of the traveler flange, and a spinning ring, the inner and outer walls of the body thereof adjacent said flange sloping inwardly and downwardly sufficiently to prevent substantial contact in operation of the inner and outer ends of the traveler with said walls of the body.

7. A double-ended spinning ring having upper and lower traveler flanges, and a connecting body, the outer surface of said body sloping inwardly and downwardly from the upper traveler flange and inwardly and upwardly from the lower traveler flange sufficiently to prevent substantial contact of the outer end of the traveler in operation with the body of the ring.

8. A double-ended spinning ring having upper and lower traveler flanges, and a connecting body, the inner surface of said body sloping inwardly and downwardly from the upper flange and inwardly and upwardly from the lower flange sufficiently to prevent substantial contact in operation between the inner end of the traveler and the body of the ring.

9. In combination, a ring and traveler for spinning, the ring being formed with an upper, substantially horizontally disposed flange having inner and outer lips for engagement by the traveler and the traveler being formed as a bowed member, of substantially uniform cross section, and with inwardly turned terminals spaced apart less than the radial width of said flange, said traveler being positioned with its separated terminals below said flange and with the body of the traveler above said flange, whereby in operation and under centrifugal force the outer end of the traveler is thrown downwardly from said flange and inwardly; and said ring being further formed with a supporting wall under said flange, the outer surface of which wall is sloped inwardly and downwardly from the said flange and lies substantially inside the line described by the outer terminal of the traveler when its outer portion is vertically rocked with its inner portion engaging the inner lip of the ring flange; whereby contact between the outer terminal of the traveler and the outer surface of said wall during the spinning operation is substantially prevented.

10. In combination, a ring and traveler for spinning, the ring being formed with an upper, substantially horizontally disposed flange having inner and outer lips for engagement by the traveler and the traveler being formed as a bowed member, of substantially uniform cross section, and with inwardly turned terminals spaced apart less than the radial width of said flange, said traveler being positioned with its separated terminals below said flange and with the body of the traveler above said flange, whereby in operation and under centrifugal force the outer end of the traveler is thrown downwardly from said flange and inwardly; and said ring being further formed with a supporting wall under said flange, the outer surface of which wall is sloped inwardly and downwardly from the said flange and lies substantially inside the line described by the outer terminal of the traveler when its outer portion is vertically rocked with its inner portion engaging the inner lip of the ring flange; whereby contact between the outer terminal of the traveler and the outer surface of said wall during the spinning operation is substantially prevented, the inner surface of said wall being also

sloped inwardly and downwardly from said flange and substantially outside the line described by the inner terminal of the traveler when the latter is vertically rocked with its inner portion in engagement with the inner edge of said flange, wherebv contact of said inner terminal with said inner surface is prevented.

In testimony whereof, have signed my name to this specification, in the presence of 10 two subscribing witnesses.

CHARLES D. LANNING.
